(57) **CLAIM**

The ornamental design for a neck pain inhibitor device, as shown and described.

DESCRIPTION

FIG. 1 is a perspective view of a neck pain inhibitor device showing my new design;

FIG. 2 is a second perspective view thereof showing the device in an open configuration;

FIG. 3 is a top elevation view thereof;

FIG. 4 is a bottom elevation view thereof;

FIG. 5 is a right-side elevation view thereof;

FIG. 6 is a left-side elevation view thereof;

FIG. 7 is a rear elevation view thereof; and,

FIG. 8 is a front elevation view thereof.

The broken lines depict portions of a neck pain inhibitor device and form no part of the claim.
